UNITED STATES PATENT OFFICE.

CHARLES F. PIKE, OF PHILADELPHIA, PENNSYLVANIA.

DESIGN FOR A TUBE.

SPECIFICATION forming part of **Design No. 26,562**, dated **January 26, 1897.**

Application filed **October 21, 1896.** Serial No. **609,621.** Term of patent **14 years.**

To all whom it may concern:

Be it known that I, CHARLES F. PIKE, a citizen of the United States, and a resident of the city of Philadelphia and State of Pennsylvania, have invented a certain new Design for a Tube, of which the following is a full, clear, and exact description, reference being had to the accompanying drawings, forming part of this specification.

- My design for the tube is shown in the annexed drawings, in which—

Figure 1 is a plan view of a tube illustrating my design. Fig. 2 is an end elevation of the same, and Fig. 3 is a sectional perspective view of the tube on an enlarged scale.

The leading feature of my design consists in the two diametrically opposite depressions

extending beyond the line of the inner walls of the tube.

Referring to the drawings, *a* represents the tube, which is circular in cross-section, and *b* represents depressions semicircular in cross-section and arranged in a vertical plane at diametrically opposite points on the tube.

What I claim is—

The design for a tube substantially as herein shown and described.

In witness whereof I have hereunto set my hand this 9th day of September, A. D. 1896.

CHARLES F. PIKE.

Witnesses:

EMMA PIKE,
WM. A. PIKE.
